UNITED STATES PATENT OFFICE.

ARTHUR JOHN ROWLEDGE, OF LONDON, ENGLAND, ASSIGNOR TO D. NAPIER & SON,
LIMITED, OF LONDON, ENGLAND.

INTERNAL-COMBUSTION ENGINE.

Specification of Letters Patent.

Patented May 11, 1920.

1,339,423.

Application filed October 15, 1917. Serial No. 198,710.

To all whom it may concern:

Be it known that I, ARTHUR JOHN ROWLEDGE, a subject of the King of England, and residing at London, in England, have invented certain new and useful Improvements 5 in Internal-Combustion Engines, of which the following is a specification.

This invention relates to internal combustion engines more especially of the type comprising three sets or blocks of cylinders arranged so that the axes of the cylinders are disposed in three planes relatively inclined about the crank shaft axis and each block of cylinders having one or a pair of cam shafts 10 mounted on the cylinder heads for operating the valves, and has for its object to effect certain improvements in a known method of driving these cam shafts off the crank shaft and also to arrange for driving one or more 15 magnetos and the necessary water and oil pumps.

In an engine of the above type in which each block of cylinders was provided with a single cam shaft mounted on the heads of these cylinders it has been proposed to drive these shafts by means of three intermediate shafts arranged truly radial with relation to the crank shaft each of the intermediate shafts carrying at its outer end a bevel wheel 20 which geared with a bevel wheel on the end of a cam shaft. At its inner end the central one of these intermediate shafts carried a bevel wheel which geared with a bevel wheel on the end of the crank shaft, while a second bevel wheel near the same end of the central intermediate shaft geared with two bevel wheels mounted respectively on the adjacent ends of the two lateral intermediate shafts. This arrangement is not however 25 adapted for use in an engine in which the cylinders are each provided with four valves the operation of which necessitates the use of two cam shafts on the heads of the cylinders in each block as it is not then convenient for various constructional reasons 30 to dispose all three intermediate shafts truly radial with relation to the crank shaft. The present improvements provide a compact and satisfactory method of driving the cam shafts combined with means for driving the magnetos and oil and water pumps off the 35 same end of the crank shaft.

The improved engine is of the type indicated inasmuch as it comprises three blocks 40 of cylinders each cylinder having four

valves operated by two cam shafts mounted on the heads of the cylinders in a block these cam shafts being driven off the crank shaft by means of three intermediate shafts. According to this invention while the central one of these intermediate shafts lies truly radial with relation to the crank shaft the two lateral intermediate shafts are disposed otherwise than truly radial with relation to the crank shaft and are inclined at different angles to the central intermediate shaft. The latter carries at its inner end a bevel wheel which gears with a corresponding wheel on the crank shaft and also has adjacent to this end two other bevel wheels which gear respectively with bevel wheels on the inner ends of the lateral intermediate shafts. On the crank shaft are mounted two bevel wheels and a spur wheel, one of these bevel wheels serving to drive the central intermediate shaft while the other drives two magnetos oppositely arranged on either side of the crank shaft. The spur wheel is employed to drive the oil and water pumps the latter being arranged on a shaft which lies parallel to the crank shaft and carries a worm wheel gearing with a worm on another shaft placed at right angles on which are one or more oil pumps.

In order to facilitate assembling and disconnecting the parts of the mechanism for driving the cam shafts each intermediate shaft is divided transversely into two parts a joint being arranged at a point in the length of the shaft which lies conveniently 50 somewhat toward the inner or crank case end of the intermediate shaft. A detachable connection is employed between these abutting ends of the two parts of the intermediate shaft the connection comprising one or 55 more longitudinal key-ways in the adjacent end portions of the shaft and a sleeve carrying one or more keys or feathers which engage these key-ways. The sleeve and keys are capable of being slid over the abutting ends of the intermediate shaft so as to couple these ends together the sleeve being retained in this position by a removable transverse pin or like device. The keys may be 60 separable from the sleeve or the latter may 65 have splines or feathers formed integral therewith.

The details of construction may vary as found desirable.

The accompanying drawings illustrate by 70

way of example how the invention may be put into practice. In these drawings,

Figure 1 is an end elevation partly in vertical section showing one form in which the invention may be applied to an engine of the type indicated the sectional portion of the figure being taken as on the line 1—1 of Fig. 2.

Fig. 2 is a side elevation on an enlarged scale and partly in vertical section of the end of the crank shaft of the engine illustrated in Fig. 1 the sectional portion being shown as on the line 2—2 of Fig. 1.

Fig. 3 is an end elevation of the water pump shown in Fig. 2, Fig. 3 being drawn on the same scale as Fig. 2.

Fig. 4 is a longitudinal section through the abutting ends of one of the intermediate shafts showing the detachable connection 20 preferably employed for coupling the ends of these shaft portions.

Fig. 5 is a longitudinal section similar to Fig. 4 but taken on an axial plane at right angles to the section shown in Fig. 4.

Like letters indicate like parts throughout the drawings.

Referring to Figs. 1 and 2 the three sets or blocks of cylinders A B and C are arranged so that the axes of these cylinders are disposed in three planes relatively inclined about the axis of the crank shaft D the angle between the block of cylinders A and the block of cylinders B being equal to the angle between the block of cylinders A and the block of cylinders C. On the head of each block of cylinders are mounted two cam shafts A' A², B' B² and C' C² these cam shafts serving to operate the twin sets of valves with which each cylinder in each block is provided. These cam shafts are geared together by spur gearing so that they rotate in opposite directions and on the end of one of the cam shafts A' B' C' is a bevel wheel A³ B³ C³ which gears with a corresponding bevel wheel E E' E² mounted on what may be termed the outer end of an intermediate shaft. These three intermediate shafts are similarly constructed and each is divided at some point in its length 50 into two parts connected by a detachable coupling which will be more particularly described hereafter. In Fig. 1 the detail construction of the central intermediate shaft only is shown in section the two portions of this shaft being designated G and G'. Of the lateral intermediate shafts H and J only a portion of the end of each shaft appears in Fig. 1 the figure showing in elevation the casings K within which these shafts are 55 closed. The bevel wheel E is mounted upon the end of the outer portion G' of the shaft and toward the inner or crank shaft end are mounted three bevel wheels G² G³ and G⁴. The bevel wheel G² is disposed at the extreme end of the shaft section G while the

wheels G³ G⁴ are arranged at some intermediate point in the length of this shaft section. The bevel wheel G² gears with a bevel wheel D' fixed on the crank shaft D toward its end. The bevel wheel G³ gears with the bevel wheel J' on the end of one lateral intermediate shaft J while the bevel wheel G⁴ gears with the bevel wheel H' on the end of the other lateral intermediate shaft H. Thus the crank shaft D drives the central intermediate shaft G G' directly through the bevel wheels D' G² and this central intermediate shaft drives the two lateral intermediate shafts H J indirectly through the bevel wheels G⁴ H' and G³ J'. 80

Each of the intermediate shafts is preferably formed hollow as shown and carried in suitable bearings arranged respectively on the end of the crank case and on the end of the head of each cylinder block while each shaft is inclosed in a casing. The bearing for the outer end of each intermediate shaft is conveniently similar to the bearing G⁵ of the central shaft G G'. The bearing for the inner ends of the lateral shafts H and J are disposed at H² and J² respectively. Toward its inner end the central intermediate shaft G G' is carried in a bearing G⁶ while a second bearing is arranged at G⁷ between the end bevel wheel G² and the bevel wheel G³ G⁴. The bevel wheels G³ G⁴ as will be seen are arranged next to each other and preferably differ slightly in size the sizes of the bevel wheels H' J' differing to a corresponding extent. In some cases 100 it may be desirable or convenient to employ only a single bevel wheel on the central intermediate shaft G G' in place of the two wheels G³ G⁴ to transmit rotation to the lateral intermediate shafts H and J. As 105 will be seen in the construction illustrated in Fig. 1 the lateral intermediate shafts H and J are necessarily arranged to form slightly different angles with the central shaft G G'. Neither of these shafts however lies truly in the plane in which lie the axes of the cylinders in the blocks A B and C. The shaft G G' however is necessarily disposed truly radial with respect to the axis of the crank shaft D. 110

As mentioned each intermediate shaft is inclosed in a casing the central portion K of which is conveniently formed of tubular sheet metal. The outer end of this tube K is carried in a socket K' screwed on to a 120 boss adjacent to the bearing G⁵ while the inner end of the tube K lies within a socket K² conveniently formed taper and screwed on to a boss K³. The tubular casing K is fixed at its outer end in the socket K' so 125 that the socket K² can be unscrewed and slid along the tube K so as to disclose the joint or coupling between the abutting ends of the shaft sections G and G'.

The casing which is employed to inclose 130

the outer end of each intermediate shaft together with the bevel wheels E and A³, E' and B³, and E² and C³ and the other gearing by means of which the cam shafts are 5 driven may be formed and arranged as found convenient. Preferably the upper part L of this casing is formed integral with the casing or cover which closes in the cam shafts A' A² and is arranged so as to 10 be readily removable. The lower part L² of this casing which carries the bearing G⁵ may be formed integral with the cylinder water jacket or suitably connected thereto.

The coupling employed for the purpose 15 of connecting the abutting ends of the two section lengths of each intermediate shaft may now be referred to. This coupling is illustrated on an enlarged scale in Figs. 4 and 5 and the construction will be described 20 more particularly with reference to the central shaft G G' but it is to be understood that a similar device is employed for coupling the two portions of each of the lateral intermediate shafts. The abutting ends of 25 the shaft lengths G G' are thickened and in each thickened part are formed one or more longitudinal key-ways G⁶ G⁷. Two such key-ways are shown in the construction 30 illustrated. Each of these key-ways is engaged by a corresponding key or feather M carried by a sleeve M' which surrounds the joint. The key-ways G⁶ extend to a greater distance along the shaft section G than the key-ways G⁷ extend along the end of the 35 shaft length G'. Thus while movement of the sleeve M' with the keys M in the outward direction along the shaft length G' is limited and cannot pass beyond the joint, on the other hand the sleeve M' together 40 with the keys M may be slid along the shaft length G until the sleeve and the keys are clear of the abutting ends of the shaft lengths G G'. When the sleeve is in that position it is possible to separate the ends 45 of the shaft lengths G G' and the outer portion can be independently rotated or removed. To make the joint the ends of the two portions G G' of the shaft are brought 50 together and the sleeve M' is then slipped over them the keys M then engaging equally the key-ways G⁶ and G⁷ and serving to couple the ends of the shaft lengths so as to transmit the drive. The sleeve M' is retained in place by a bolt or pin M² which 55 passes transversely through the sleeve and through the abutting ends of the shaft lengths G G' semicircular notches being formed in the ends of these shaft lengths to allow of the passage of the bolt. The bolt 60 M² thus also helps to lock the two ends of the shaft lengths together. The sleeve M' is carried externally toward one end in a cylindrical guide or bearing M³ (Fig. 1) which is in turn mounted in the boss K³. 65 By thus forming each intermediate shaft in

two portions connected by a device such as described or by some other detachable coupling of a like nature it is possible to set the timing of the cam shafts carried on the cylinder heads after the parts have been assembled. Thus when the cylinders are in place the shaft length G' can be rotated to adjust the timing of the cam shafts A' A² before the shaft length G' is coupled to the shaft length G. As already mentioned access can readily be had to the coupling by unscrewing the socket K² and sliding this up along the tubular casing K.

Toward the end of the crank shaft D and next to the bevel wheel D' is mounted a second bevel wheel D² as shown in Fig. 2. Two similar bevel wheels N (Fig. 1) gear with this bevel wheel D² each of these wheels N being mounted on a short shaft N' of suitable construction carried in conveniently situated bearings N² the shaft being constructed and arranged so that a magneto may be coupled thereto. As will be seen in Fig. 1 these wheels N are oppositely disposed with relation to the axis of the crank shaft D but the shafts on which the wheels N are mounted are conveniently arranged otherwise than in line with each other though these shafts lie at right angles to the crank shaft axis.

A shaft O carried in suitable bearings and arranged parallel to the axis of the crank shaft D has on one end thereof a toothed wheel O' which gears with a pinion D³ mounted on the end of the crank shaft 100 D. The shaft O also carries a skew gear wheel O² through which rotary motion is transmitted to an oil pump P of suitable type and construction the axis of the pump lying at right angles to the axis of the shaft 105 O. On the end of the shaft O is mounted the rotary member Q of a centrifugal water pump which as shown in Fig. 3 has three tangentially arranged deliveries Q' Q² Q³ which respectively communicate with the 110 water jacket of the cylinder blocks B, A and C. The pump also has the usual intake Q⁴. The disposition of the parts is such that in an end view of the engine the water pump Q lies centrally with the magnetos driven 115 by the gear wheels N, D² off the crank shaft disposed on each side and behind the water pump while the oil pump P lies transversely but centrally behind the water pump. Where the engine is employed for use on 120 aircraft the propeller is mounted at the opposite end of the crank shaft and driven either direct or through gearing as found desirable.

What I claim as my invention and desire 125 to secure by Letters Patent is:—

1. In an internal combustion engine of the type comprising three blocks of cylinders disposed with the cylinder axes in three planes inclined to each other and having 130

overhead valve cam shafts and two magnetos; the improved means for driving the cam shafts and magnetos comprising, a pair of bevel gears secured to the crank shaft of the engine at one end thereof, means to drive said cam shafts including a shaft radially disposed with respect to the crank shaft axis having a bevel gear meshing with one of the bevel gears on the crank shaft adapted to 5 drive a cam shaft of one block, similar shafts for driving the cam shafts of the other blocks, each disposed to intersect the axis of said radial shaft above the axis of the crank shaft, bevel gears for driving said 10 last mentioned two shafts from the radial shaft and a pair of bevel gears meshing with the other gear on the crank shaft for driving the magnetos.

2. In an internal combustion engine of 20 the type comprising three blocks of cylinders disposed with the cylinder axes in three planes inclined to each other and having overhead valve cam shafts and two magnetos; the improvement comprising means 25 to support said magnetos with their axes at right angles to the crank shaft axis and on opposite sides thereof, a pair of bevel gears secured to the crank shaft, means for driving said cam shafts from one of said gears 30 and means for driving the magnetos from the other.

3. In an internal combustion engine of 35 the type comprising three blocks of cylinders disposed with their cylinder axes in three planes inclined to each other and having overhead valve cam shafts, a pair of magnetos and a water circulating pump; the improvement comprising means to support said magnetos with their axes at right 40 angles to the crank shaft axis and on opposite sides thereof, means to support the water pump with its axis parallel to the crank shaft axis, a pair of bevel gears and a spur gear secured to the crank shaft; 45 means for driving said cam shafts from one of said bevel gears, means to drive the magnetos from the other bevel gear and means for actuating the pump from the spur gear.

4. In an internal combustion engine of the type comprising three blocks of cylinders disposed with their cylinder axes in 50 three planes inclined to each other and having overhead valve cam shafts, a pair of magnetos, an oil pump and a water circulating pump; means to support said magnetos 55 at one end of the crank shaft with their axes at right angles to and on opposite sides of the crank shaft axis, means to support the water pump in front of the said end of the crank shaft with its shaft parallel to the 60 crank shaft, three gears secured to the crank shaft at said end, means actuated by one gear to operate said cam shafts, means for driving the magnetos from the second gear, means to drive the water pump shaft from 65 the third gear and means for driving the oil pump from the water pump shaft.

5. In an internal combustion engine of the type comprising three blocks of cylinders disposed with the cylinder axes in three 70 planes inclined to each other and having overhead valve cam shafts and two magnetos; the improved means for driving the cam shafts and magnetos comprising, a pair of bevel gears secured to the crank shaft of 75 the engine at one end thereof, means for driving said cam shafts from one of said gears and means for driving the magnetos from the other, said cam shaft driving means including a shaft disposed substantially radially relative to the crank shaft axis and connected to actuate the cam shafts of one block of cylinders, and shafts driven from said radially disposed shaft to actuate the cam shafts of the other blocks of 80 cylinders, said radial shaft and shafts driven therefrom comprising two sections 85 detachably secured together.

In testimony whereof I have signed my name to this specification in the presence of 90 two subscribing witnesses.

ARTHUR JOHN ROWLEDGE.
